ABSTRACT OF THE DISCLOSURE

Compounds of the formula

R^1-CO-R^2

wherein R^1 is a natural fatty acid residue, and R^2 is

R^3 is alkyl, alkenyl, cycloalkyl, alkylcycloalkyl, hydroxy-cycloalkyl, alkoxy-cycloalkyl, aryl, alkylaryl, hydroxyaryl, alkoxyaryl, halogenoaryl, halogenoalkylaryl, alkoxyhalogenoaryl, halogenoalkylhalogenoaryl, aralkyl, alkylaralkyl, hydroxyaralkyl or alkoxyaralkyl having not more than 36 carbon atoms, R^4 is H or an R^3 radical, and R^5 is bivalent alkylene, oxygen-interrupted bivalent alkylene or oxygen-interrupted bivalent alkenylene, R^5 having not more than 7 carbon atoms, are excellently suitable for use as agents for reducing elevated cholesterol level in the blood.

The present invention relates to a novel type of cholesterol-lowering agents. More particularly, it relates to agents which are useful for the reduction of the elevated blood cholesterol level.

Atherosclerosis is one of the problems in the adult diseases, which have not come to a satisfactory solution. Although the cause of atherosclerosis has not yet been brought to light in spite of the discussions in the academic world, it has broadly been recognized that one of the most significant histopathological manifestations of atherosclerosis is the deposition of lipids in the blood vessels. Accordingly, the researchers have been directed to the disturbed metabolism of lipids, and attention has been paid to the extraordinarily elevated level of cholesterol in the blood.

A number of experimental and clinical facts have been reported which point out the relationship between atherosclerosis and elevated blood cholesterol level. Hence, the development of agents to reduce elevated blood cholesterol level is one of the most important keys for prevention against or prevention of atherosclerosis.

Concentrated efforts have heretofore been made for the development of such agents for lowering cholesterol, not a few compounds have been tested clinically, but none of them are satisfactory. Some of the cholesterol-lowering agents are fairly excellent in their effectiveness but are inevitably bound up with harmful side effects which are

2

not negligible, and the others are insufficient in their effectiveness, namely needing administration in abundant doses.

The sole group of compounds practically employed nowadays for the purpose comprises unsaturated fatty acids, especially linoleic acid. The reason why linoleic acid is employed is in its safety or harmlessness to the human body. As regards the effectiveness, however, it is not so high and is uncertain and indefinite. Accordingly, administration in abundant doses is necessary to realize at least appreciable efficacy as cholesterol-lowering agents.

Duly recognizing the disadvantages of the agents to reduce the blood cholesterol level, heretofore proposed and employed, and in order to meet the demand for novel superior agents, we have conducted broad researches as to variety of compounds, and have previously found that N-substituted octadecadienoic acid amide compounds especially N-substituted linoleic acid amide, fulfill the requirements and made patent application in this regard.

20 The present invention is based on the discovery that natural fatty acid amide derivatives are as effective as linoleic acid amide derivatives concerning the lowering of cholesterol level in blood and the natural fatty acid amide of the present invention is far advantageous from the commercial view point. Such specific biological properties of the natural fatty acid amide derivatives have never been reported before the present invention.

Thus, an object of the present invention is to provide novel type of cholesterol-lowering agents having superior effectiveness which may be used to reduce the elevated level of cholesterol in the blood, without appreciable toxicities during the course of long administration, as compared with the known agents, with low cost and advantageously in commercial point of view. Other objects and advantages would be apparent from the following descriptions.

In order to accomplish these objects the present invention provides a novel group of N-substituted natural fatty acid amides represented by the following general formula:

45 wherein R^1 stands for a natural fatty acid residue, R^3 is a member selected from the group consisting of alkyl, alkenyl, cycloalkyl, alkylcycloalkyl, hydroxycycloalkyl, alkoxy-cycloalkyl, aryl, alkylaryl, hydroxyaryl, alkoxyaryl, halogenoaryl, halogenoalkylaryl, alkoxyhalogenoaryl, halogenoalkylhalogenoaryl, aralkyl, alkylaralkyl, hydroxyaralkyl and alkoxyaralkyl having not more than 36 total carbon atoms, and R^4 is a member selected from the group consisting of hydrogen atom and the radicals described with respect to R^3 .

55 Speaking of the biological activity, the present natural fatty acid amides are superior to the cholesterol-lowering agent and preventing agent of atherosclerosis now commonly employed concerning the cholesterol lowering effect, which was tested by using experimental animals such as mouse, rat and rabbit. In other words, the natural fatty acid amides of the present invention do not possess abominable toxicity and side effect even when continuously administered for a long period of time to mouse and rat.

60 For the production of the present natural fatty acid amides, any of the processes known for the amide prep-

aration from oil, its hydrolyzate or functional derivatives of the acid and an amine may be employed.

For example (1) a natural fat is hydrolyzed and the resulting fatty acid is reacted directly with an amine of the formula R^2-H (R^2 is a substituted amino radical

as defined before) in the presence of a dehydrating agent such as a disubstituted carbodiimide compound, in an aqueous or organic solvent, (2) a natural fat is hydrolyzed and the resulting fatty acid is converted to fatty acid chloride (Organic Synthesis, vol. 37, p. 66), and the resulting chloride is contacted with at least equimolar amount of the amine in the presence of a basic condensing agent, and (3) a natural oil or lower alkyl esters of natural fatty acid is directly reacted with the amine in the presence or absence of solvent and in the presence of or absence of condensing agent, this is the simplest method.

Examples of the natural oils mentioned herein are as follows: as a vegetable oil, hempseed oil, linseed oil, perilla oil, oiticica oil, kaya oil, walnut oil, poppyseed oil, safflower oil, water melon oil, soybean oil, sunflower oil, rice bran oil, pumpkin oil, kaoliang oil, sesame oil, corn oil, rape oil, cottonseed oil, olive oil, cashew oil, tsubaki oil, ergot oil, castor oil, peanut oil, palm oil, palm kernel oil, coconut oil, and the like oils; as an animal oil, beef tallow, lard, bone oil, horse fat, locust oil, crysalis oil, shark oil, cuttlefish oil, sardine oil, flatfish oil, horse mackerel oil, mackerel oil, saury pike oil, herring oil, cod oil, trout oil, grey mullet oil, tunny oil, menuke oil, menhaden oil, eel oil, various kinds of whale oils and the like oils or residual oils of land or marine animals, without distinction of origin, for example, body oil, skin oil, head oil, liver oil or egg oil thereof.

In case of a dehydration condensation method using disubstituted carboximides, and dehydrogen halide condensation method through acid halide, these oils are hydrolyzed by suitable methods, for example, using a mixture of an alkaline hydroxide and an alcohol, water, acetone or other solvents, these solvents being used alone or as a mixture, thereby to yield a mixture of fatty acids.

The resulting fatty acids are employed for the synthesis of their amides without or after removing most of saturated fatty acids simply and with good efficiency by winterizing method, urea method, recrystallization method, metal salt method, distillation method or other methods.

In case of an acid halide method, the fatty acids are converted without any trouble in good yield according to the methods using thionyl chloride, phosgene, dimethylformamide and the like, which have been investigated by many investigators. If necessary, it is possible to use bromides or iodides instead of chloride, but not important.

Typical amines of the formula R^2-H (R^2 is as defined before) employed in the present invention are as follows: it is not necessary to say that it is proved by the present inventors to be able to employ other amines, as far as they are primary or secondary amines, without any trouble in proceeding of the present invention, as mono- or dialkylamines, such lower alkylamines as mono- or dimethylamine, mono- or diethylamine, mono- or di-n- or i-propylamine, and mono- or di-n-, i- or t-butylamine and such higher alkylamines as mono- or didodecylamine, mono- or dialmethylamine and mono- or distearylamine; as mono- or dialkenylamines, such amines as mono- or allylamine, mono- or dioleylamine, mono- or dilinoleylamine and mono- or dilinolenylamine; as cycloalkylamines or their derivatives, such amines as cyclopentylamine, cyclohexylamine, cycloheptylamine, N-methyl-, N-ethyl-, N-n- or i-propyl or N-n-, i-, t-butylcyclopentylamine, N-methyl- or N-ethylcyclohexylamine, N-methyl-, N-ethyl-,

N-n- or i-propyl or N-n,i,t-butylcycloheptylamine, N-cyclohexyl- or N-phenyl-N-cyclohexylamine; lower alkylcycloalkylamine substituted by one or more of methyl ethyl, n- or i-propyl or n-, i- or t-butyl radical in at least an ortho, meta or para position, hydroxycyclohexylamine substituted by one or more of hydroxy radicals in at least a 2, 3, or 4 position and cycloalkylamine, substituted by one or more of lower alkyl and hydroxy radical at least a 2, 3 or 4 position, lower alkoxyalkylamine substituted by methoxy, ethoxy or other alkoxy radicals in at least a 2, 3 or 4 position; as aromatic amines, for example, aniline, diphenylamine, benzylamine, lower alkylaniline substituted by one or more methyl, ethyl, n-, i-propyl and n,i,t-butyl radicals in at least an ortho, meta or para position, N-methyl- or N-ethyl-amine, hydroxyaniline substituted by one or more hydroxy radicals in at least an ortho, meta or para position, lower alkoxyaniline substituted by one or more of methoxy or ethoxy, n-, i-propoxy, n-, i-, t-butoxy radical in at least an ortho, meta or para position, halogenoaniline substituted by one or more of fluorine, chlorine, bromine or iodine atom in at least an ortho, meta or para position, trifluoromethylaniline substituted by one or more of trifluoromethyl radicals in at least an ortho, meta or para position, aniline substituted by one or more of lower alkyl, hydroxy, halogen, lower alkoxy or trifluoromethyl radicals, such as 2,4,6-trimethylaniline and fluorotoluidines, dibenzylamine, lower alkylbenzylamine such as α -methylbenzylamine, α -ethylbenzylamine, α -n,i-propyl, α -n,i,t-butyl and the like, lower alkylbenzylamine substituted by methyl, ethyl, propyl, butyl or other lower alkyl radicals, lower alkoxybenzylamine substituted by methoxy, ethoxy, n-, i-propoxy, n-, i-, t-butoxy or other lower alkoxy radicals in at least an ortho, meta, or para position, hydroxybenzylamine substituted in at least an ortho, meta or para position, and benzylamines substituted by one or more of lower alkyl, lower alkoxy or hydroxy radicals.

In case of the carboximide method, the di-substituted carboximide having the following general formula, $R^6-N=C=N-R^6$ wherein R^6 represents a member selected from the group consisting of alkyl, phenyl, cycloalkyl and aralkyl radicals, is employed as condensation agents, thereby to yield fatty acid amides in good yield.

Typical examples of di-substituted carbodiimide are as follows: as dialkylcarbodiimides di-isopropylcarbodiimide and the like, as dicycloalkyl carbodiimides dicyclohexylcarbodiimides and the like, and as diaryl carbodiimides diphenylcarbodiimides, dibenzylcarbodiimides and the like. It is not necessary to say that carbodiimides other than those above-mentioned are employed without any trouble.

The condensation reaction between a hydrolyzed natural fats and an amine using a carbodiimide is well proceeded at room temperature, but when the reaction is vigorously exothermic, if necessary, it may be allowed to cool.

Water and almost all of organic solvents can be employed as a solvent.

They are: ethers such as diethyl ether, tetrahydrofuran and dioxane; esters such as methyl acetate, ethyl acetate, ethyl acetate and butyl acetate; ketones such as acetone, methyl ethyl ketone and methyl isobutyl ketone; halogenoalkanes such as chloroform, carbon tetrachloride and ethylene dichloride; hydrocarbonic solvents such as cyclohexane, n-hexane, petroleum ether, gasoline, benzene and toluene; and water.

They are employed alone or in the form of a mixture thereof in optional proportion.

The reaction procedure is as follows: The natural fatty acid, the amine and the di-substituted carbodiimide mentioned above, at least one of them is dissolved in a solvent, are mixed at room temperature or under cooling, if required, and the mixture is allowed to stand for 3 to 24 hours while being stirred at need. To the reaction mixture is added a small portion of acetic acid to decompose the

excess carbodiimide and formed urea derivative is filtered off thereby to yield fatty acid amides in the filtrate.

In case of the acid halide method, basic compounds are employed in case of necessity as an auxiliary agent of condensation. Typical examples of the auxiliary agent are hydroxide, carbonate or bicarbonate of alkali metal such as lithium, sodium or potassium, or those of alkali earth metal such as calcium or barium; tertiary amines such as pyridine, picoline, lutidine, trimethylamine, triethylamine, dimethylaniline or diethylaniline. An excess amount of reactant amines may also be used as the auxiliary agent.

It is possible to recover and thereafter to employ the amines above-mentioned and excess amount of reactant amines in the present method. Typical examples of solvents employed in this method are water; ketones such as acetone, methyl ethyl ketone and methyl isobutyl ketone, esters such as methyl acetate, ethyl acetate, propyl acetate or butyl acetate; hydrocarbonic solvents such as n-hexane, cyclohexane, benzene and toluene; ethers such as diethyl ether, tetrahydrofuran and dioxane; halogeno-alkanes such as dichloroethylene, chloroform and carbon tetrachloride; and tertiary amines such as dimethylformamide, pyridine, trimethylamine or the other tertiary amines, or a mixture thereof in optional proportion.

Though the reaction temperature, of course, generally depends on the employed solvent, it is within a temperature range of from -20° C. to near the boiling point of the solvent. The reaction is preferably carried on in an atmosphere of such an inactive gas as nitrogen, helium and the like. Thus, the amide derivatives of the objective products are obtained under relatively mild conditions in high yields and simplicity without oxidation of the reactant.

In case of the direct reaction of the natural oil or lower alkyl ester of natural fatty acid and the amine the reaction method for producing the amide derivatives is as follows: That is, about 1 mol of the said oils and 1 to 100 equivalent mols of the said amines are mixed in the absence or presence of solvents such as methanol, ethanol or the like, such aromatic hydrocarbons as benzene, toluene, xylene or the like, such halogenoalkanes as methylenechloride, chloroform, carbon tetrachloride or the like, and such alkenes or alkanes as petroleum ether, benzene, gasoline, ligroin or cyclohexane, such ethers as tetrahydrofuran, dioxane and the like, or a mixture thereof, and the mixture is subjected to the reaction in the absence or presence of catalyst amount or equimolar amount to the amine of an auxiliary agent of condensation, such as alkoholate of alkali metal, i.e. lithium methylate, lithium ethylate, sodium methylate, sodium ethylate, potassium-t-butylate and the like, or acidic auxiliary agents, i.e. p-toluenesulfonic acid and the like, thereby to yield the amide derivatives. In this reaction, a formal alcohol may be removed from the reaction system.

It is a matter of course that even absence of any solvents and any auxiliary agents can sufficiently accomplish the purpose.

In case of using amines having lower boiling point, if necessary, an autoclave may be employed but in case of another amines the reaction mixture is stirred under atmospheric pressure while being heated at need, thereby easily to yield the objective amide.

In carrying out the reaction, a mixture of respective substance is stirred at a suitable temperature of between room temperature and 400° C. for about 3 hours to a month.

If necessary, the reaction is carried on in an atmosphere of an inactive gas such as nitrogen, helium and the like to prevent from producing undesirable byproducts and coloring, thereby to yield the objective product, which is, at need, subjected to a fractional distillation, recrystallization using a petroleum hydrocarbon, acetone or the like or urea method to remove saturated fatty acid amides. If alkali alcoholate is used as an auxiliary agent, conju-

gated double bond isomer are partially obtained. However, the present invention confirmed that saturated and isomerized fatty acid amides affect on the human body no undesirable effect.

The process of the invention is described in more detail with reference to the following examples, which are however to be construed for the purpose of illustration and not of the limitation.

EXAMPLE 1

Ten grams of hydrolyzed product of linseed oil, 5 g. of isopropylamine and 9 g. of dicyclohexylcarbodiimide are mixed together in ethyl ether and the mixture is allowed to stand overnight at room temperature. The excess of dicyclohexylcarbodiimide is decomposed with acetic acid and the decomposed product is filtered off. The filtrate is washed successively with an acid, an aqueous alkali, and water and dried. The solvent is removed from the filtrate and the residue is distilled in vacuo to yield 9.5 g. of N-isopropyl linseed oil fatty acid amide, B.P. 200-207° C./0.03 mm. Hg.

EXAMPLE 2

Ten grams of safflower oil fatty acid, from which saturated fatty acids have been roughly removed by treating with urea, 10 g. of oleylamine and 9 g. of diisopropylcarbodiimide are treated in benzene in a similar way as in Example 1, to yield 10 g. of N-oleyl safflower oil fatty acid amide, which is semi solid and can not be distilled.

EXAMPLE 3

Ten grams of soybean oil fatty acid, from which saturated fatty acids have been roughly removed by low temperature recrystallization method using acetone, 5 g. of allylamine and 9 g. of diphenylcarbodiimide are treated in tetrahydrofuran in a similar way as in Example 1, to yield 8.1 g. of N-allyl soybean oil fatty acid amide, B.P. 190-208° C./0.04 mm. Hg.

EXAMPLE 4

Ten grams of rice bran oil fatty acid, 5 g. of cyclopentylamine and 9 g. of dicyclohexylcarbodiimide are treated in chloroform in similar way as in Example 1 to yield 7.9 g. of N-cyclopentyl rice bran oil fatty acid amide, B.P. 202-224° C./0.02 mm. Hg.

EXAMPLE 5

Ten grams of hydrolysed product of sunflower oil, 5 g. of cyclohexylamine and 9 g. of dibenzylcarbodiimide are reacted in carbon tetrachloride to yield 8.1 g. of N-cyclohexyl sunflower oil fatty acid amide, B.P. 201-221° C./0.03 mm. Hg.

EXAMPLE 6

Ten grams of sesame oil fatty acid, from which saturated fatty acids have been roughly removed by using lead acetate, 5 g. of 4-methylcyclohexylamine and 9 g. of dicyclohexylcarbodiimide are treated in benzene to yield 9.0 g. of N-4-methylcyclohexyl sesame oil fatty acid amide, B.P. 200-215° C./0.04 mm. Hg.

EXAMPLE 7

Ten grams of sesame oil fatty acid, 5 g. of 3-methylcyclohexylamine and 9 g. of dicyclohexylcarbodiimide are treated in benzene to yield 8.2 g. of N-3-methylcyclohexyl sesame oil fatty acid amide, B.P. 200-221° C./0.03 mm. Hg.

EXAMPLE 8

Corn oil is ester-exchanged with methanol and the product is distilled in vacuo and the fraction boiling at 145-150° C./0.05 mm. Hg. is collected, whereby methyl ester of the saturated fatty acids are roughly removed. Ten grams of the hydrolysate fatty acids are roughly removed. Ten grams of the hydrolysate of this fraction, 5 g. of 2-methylcyclohexylamine and 9 g. of dicyclohexylcarbodiimide are treated in benzene to yield 8.3 g. of

N-2-methylcyclohexyl corn oil fatty acid amide, B.P. 198-213° C./0.03 mm. Hg.

EXAMPLE 9

Ten grams of hydrolyzed product of rape oil, 5 g. of 2-ethylcyclohexylamine and 9 g. of dicyclohexylcarbodiimide are treated in benzene to yield 9.0 g. of N-2-ethylcyclohexyl rape oil fatty acid amide, B.P. 188-205° C./0.02 mm. Hg.

EXAMPLE 10

Ten grams of cottonseed oil fatty acid, 5 g. of 3-isopropylcyclohexylamine and 9 g. of dicyclohexylcarbodiimide are treated in dioxane to yield 8.8 g. of N-3-isopropylcyclohexyl cottonseed oil fatty acid amide, B.P. 196-213° C./0.03 mm. Hg.

EXAMPLE 11

Ten grams of olive oil fatty acid, 5 g. of 2-hydroxycyclohexylamine and 9 g. of dicyclohexylcarbodiimide are treated in dichloroethane to yield 9.3 g. of N-2-hydroxycyclohexyl olive oil fatty acid amide, B.P. 193-209° C./0.02 mm. Hg.

EXAMPLE 12

Ten grams of castor oil fatty acid, 5 g. of 3-hydroxycyclohexylamine and 9 g. of dicyclohexylcarbodiimide are treated in ethyl ether to yield 6.3 g. of N-3-hydroxycyclohexyl castor oil fatty acid amide, B.P. 195-215° C./0.05 mm. Hg.

EXAMPLE 13

Ten grams of peanut oil fatty acid, from which saturated fatty acids have been previously removed by treating with urea, 5 g. of 2-propylcyclohexylamine and 9 g. of dicyclohexylcarbodiimide are treated in methyl acetate to yield 7.9 g. of N-2-propylcyclohexyl peanut oil fatty acid amide, B.P. 200-219° C./0.06 mm. Hg.

EXAMPLE 14

Ten grams of fish liver oil fatty acid, 5 g. of N-methyl-N-cyclohexylamine and 9 g. of dicyclohexylcarbodiimide are treated in ethyl ether to yield 10.3 g. of N-methyl-N-cyclohexyl fish liver oil fatty acid amide, B.P. 203-215° C./0.02 mm. Hg.

EXAMPLE 15

Ten grams of chrysalid oil fatty acid, 5 g. of cycloheptylamine and 9 g. of dicyclohexylcarbodiimide are treated in benzene to yield 8.0 g. of N-cycloheptyl chrysalid oil fatty acid amide, B.P. 203-217° C./0.03 mm. Hg.

EXAMPLE 16

Ten grams of shark oil fatty acid, 5 g. of pyrrolidine and 9 g. of dicyclohexylcarbodiimide are treated in benzene to yield 8.3 g. of N-tetramethylene shark oil fatty acid amide, B.P. 200-223° C./0.03 mm. Hg.

EXAMPLE 17

Ten grams of shark oil fatty acid, from which saturated fatty acids are previously roughly removed as lithium salt, 5 g. of piperidine and 9 g. of dicyclohexylcarbodiimide are treated in benzene to yield 7.9 g. of N-pentamethylene shark oil fatty acid amide, B.P. 190-209° C./0.02 mm. Hg.

EXAMPLE 18

Ten grams of cuttlefish oil fatty acid, 5 g. of morpholine and 9 g. of dicyclohexylcarbodiimide are treated in benzene to yield 8.2 g. of cuttlefish oil fatty acid amide derivative having the formula of

B.P. 199-216° C./0.03 mm. Hg.

EXAMPLE 19

Ten grams of cuttlefish oil fatty acid, from which saturated fatty acids are roughly removed by treating with

urea, 5 g. of hexamethyleneimine and 9 g. of dicyclohexylcarbodiimide are treated in benzene to yield 8.0 g. of N-hexamethyleneimino cuttlefish oil fatty acid amide, B.P. 200-218° C./0.02 mm. Hg.

EXAMPLE 20

Ten grams of sardine oil fatty acid, 5 g. of m-toluidine and 9 g. of dicyclohexylcarbodiimide are treated in benzene to yield 7.9 g. of N-m-tolyl sardine oil fatty acid amide, B.P. 197-223° C./0.02 mm. Hg.

EXAMPLE 21

Ten grams of mackerel oil fatty acid, 5 g. of aniline and 9 g. of dicyclohexylcarbodiimide are treated in ether to yield 9.1 g. of N-phenyl mackerel oil fatty acid amide, B.P. 195-203° C./0.03 mm. Hg.

EXAMPLE 22

Ten grams of mackerel oil fatty acid, 5 g. of 2,4,6-trimethylaniline and 9 g. of dicyclohexylcarbodiimide are treated in ether to yield 10 g. of N-2,4,6-trimethylphenyl mackerel oil fatty acid amide, B.P. 197-219° C./0.03 mm. Hg.

EXAMPLE 23

Ten grams of saury pike oil fatty acid, 5 g. of p-fluorooraniline and 9 g. of dicyclohexylcarbodiimide are treated in ethyl ether to yield 11 g. of N-p-fluorophenyl saury pike oil fatty acid amide, B.P. 202-218° C./0.03 mm. Hg.

EXAMPLE 24

Ten grams of herring oil fatty acid, 5 g. of m-trifluoromethylaniline and 9 g. of dicyclohexylcarbodiimide are treated in ethyl ether to yield N-m-trifluoromethylphenyl herring oil fatty acid amide, B.P. 200-215° C./0.02 mm. Hg.

EXAMPLE 25

Ten grams of whale oil fatty acid, 5 g. of o-anisidine and 9 g. of dicyclohexylcarbodiimide are treated in ethyl ether to yield 8.3 g. of N-o-methoxyphenyl whale oil fatty acid amide, B.P. 209-219° C./0.03 mm. Hg.

EXAMPLE 26

Ten grams of whale oil fatty acid, 5 g. of m-anisidine and 9 g. of dicyclohexylcarbodiimide are treated in ethyl ether to yield 9.2 g. of N-m-methoxyphenyl whale oil fatty acid amide, B.P. 207-220° C./0.03 mm. Hg.

EXAMPLE 27

Ten grams of sperm head oil fatty acid, 5 g. of p-t-butylaniline and 9 g. of dicyclohexylcarbodiimide are treated in ethyl ether to yield 9.3 g. of N-p-t-butylphenyl sperm head oil fatty acid amide, B.P. 194-209° C./0.03 mm. Hg.

EXAMPLE 28

Ten grams of sperm blubber oil fatty acid, 5 g. of p-hydroxyaniline and 9 g. of dicyclohexylcarbodiimide are treated in ethyl ether to yield 9.5 g. of N-p-hydroxyphenyl sperm blubber oil fatty acid amide, B.P. 201-219° C./0.03 mm. Hg.

EXAMPLE 29

Ten grams of razorback oil fatty acid, 5 g. of diphenylamine and 9 g. of dicyclohexylcarbodiimide are treated in ethyl ether to yield 9.3 g. of N,N-diphenyl razorback oil fatty acid amide, B.P. 209-223° C./0.03 mm. Hg.

EXAMPLE 30

Ten grams of fish liver oil fatty acid, 5 g. of N-methylaniline and 9 g. of dicyclohexylcarbodiimide are treated in ethyl ether to yield 9.4 g. of N-methyl-N-phenyl fish liver oil fatty acid amide, B.P. 200-214° C./0.03 mm. Hg.

EXAMPLE 31

Ten grams of fish liver oil fatty acid, 5 g. of N-methylcyclohexylamine and 9 g. of dicyclohexylcarbodiimide are treated in ethyl ether to yield 10.3 g. of N-methyl-N-

cyclohexyl fish liver oil fatty acid amide, B.P. 203-215° C./0.02 mm. Hg.

In similar way as in Examples 1 to 31, the following results are obtained.

are dissolved in 50 ml. of benzene and the mixture is allowed to stand overnight at room temperature. Acetic acid is added thereto decompose the excess amount of dicyclohexylcarbodiimide and the mixture is filtered to

NOTE :

1. A means cyclohexylamine
2. B means o-toluidine
3. C means p-ethoxyaniline
4. D means N-ethylaniline
5. The fatty acids attached with the mark * are used after removing saturated fatty acid.

EXAMPLE 66

Soybean oil is hydrolyzed in 1 N solution of sodium hydroxide in methanol and the resulting soybean oil fatty acid is treated with urea and methanol to remove saturated fatty acid.

Ten grams of the fatty acid, thus obtained, 5 g. of α -methylbenzylamine and 9 g. of dicyclohexylcarbodiimide

separate the decomposed product off. Then the filtrate is washed successively with 5% hydrochloric acid, 5% sodium carbonate aqueous solution and water, and dried over anhydrous sodium sulfate. Upon evaporation of the solvent, the residue is distilled in vacuo to yield 12 g. of N- α -methylbenzyl soybean oil fatty acid amide, B.P. 200-203° C./0.04 mm. Hg., n_D^{27} 1.4844.

In similar way as in Example 66, the following results are obtained.

Example No.:	Fatty acid	Amine	Solvent	B.P. ° C./mm. Hg	R ⁶ in the disubstituted carbodiimide of the formula R ⁶ -N=C=N-R ⁶

¹ The fatty acid attached with (1) is used after roughly removing saturated fatty acids with the urea method.

² The fatty acid attached with (2) is used after removing saturated fatty acids with the acetone-recrystallization method.

³ The fatty acid attached with (3) is used after roughly removing saturated fatty acids with the distillation method.

EXAMPLE 80

Ten grams of linseed oil fatty acid chloride is dropped into 40 ml. of methyl isobutyl ketone solution containing 4.5 g. of monoethylamine and 5 g. of potassium carbonate at a temperature of 0° C. while being vigorously stirred. The reaction mixture is allowed to stand overnight and stirred for 2 hours at a temperature of 40° C., followed by filtration to remove the precipitate. The filtrate is evaporated, and the residue is dissolved in ethyl ether, washed successively with 5% hydrochloric acid, aqueous 5% sodium carbonate solution and water, dried over anhydrous sodium sulfate and evaporated to remove ether. The product thus obtained is distilled in vacuo, thereby to yield 9.8 g. of N-ethyl linseed oil fatty acid amide, B.P. 200-213° C./0.05 mm. Hg.

EXAMPLE 81

Ten grams of rice bran oil fatty acid chloride, from which saturated fatty acids have been nearly removed with urea, is dropped into 30 ml. of benzene solution containing 5 g. of allylamine and 6 g. of trimethylamine at a temperature of 10° C. The reaction mixture is treated in similar way as in Example 80. The obtained benzene layer is washed successively with 5% hydrochloric acid, aqueous 5% sodium carbonate solution and water, and dried and evaporated to remove benzene, thereby to yield 9.3 g. of N-allyl rice bran oil fatty acid amide, B.P. 190-214° C./0.03 mm. Hg.

EXAMPLE 82

Ten grams of soybean oil fatty acid chloride is dropped into a mixture of 10 g. of oleylamine and 30 ml. of pyridine at a temperature of 0° C. The reaction mixture is treated in similar way as in Example 80. The crystals thus obtained are subjected to recrystallization with petroleum ether or acetone, thereby to yield semi-solid N-oleyl soybean oil fatty acid amide.

EXAMPLE 83

Ten grams of safflower oil fatty acid chloride is dropped into 40 ml. of acetone solution containing 5 g. of cyclo-

35 pentyamine and 5 g. of potassium carbonate at a temperature of -5° C. The reaction mixture is treated in similar way as in Example 80, thereby to yield 10.1 g. of N-cyclopentyl safflower oil fatty acid amide, B.P. 202-224° C./0.02 mm. Hg. If necessary, it is possible to remove saturated amides from the product obtained above by recrystallization from petroleum ether or acetone.

EXAMPLE 84

45 Ten grams of sunflower oil fatty acid chloride is dropped into 50 ml. of acetone solution containing 3 g. of cyclohexylamine and 2 g. of potassium hydroxide at a temperature of 0° C. The reaction mixture is treated in similar way as in Example 80, thereby to yield 10.3 g. of N-cyclohexyl sunflower oil fatty acid amide, B.P. 200-218° C./0.03 mm. Hg.

EXAMPLE 85

55 Ten grams of sesame oil fatty acid bromide, from which saturated fatty acids have been previously removed with lead acetate, is dropped into 40 ml. of tetrahydrofuran solution containing 4 g. of 4-methylcyclohexylamine and 2 g. of trimethylamine at a temperature of 0° C. The reaction mixture is treated in similar way as in Example 80, thereby to yield 10.5 g. of N-4-methylcyclohexyl sesame oil fatty acid amide, B.P. 203-218° C./0.03 mm. Hg.

EXAMPLE 86

Corn oil is transesterized with methanol and the resulting methyl ester is fractionated to obtain a fraction of 145-150° C./0.05 mm. Hg, which is almost freed from the ester of saturated fatty acids and the fraction is hydrolyzed and chlorinated, thereby to obtain the acid chloride. Ten grams of the acid chloride is treated in methyl acetate with 4 g. of 3-methylcyclohexylamine and 4 g. of sodium carbonate to yield 10.2 g. of N-3-methylcyclohexyl corn oil fatty acid amide, B.P. 193-209° C./0.03 mm. Hg.

In similar way as in Examples 80 to 85, the following results are obtained.

¹ The acid chloride attached with (*) is that from which saturated fatty acids have been previously removed with urea.

² The acid chloride attached (*) is that from which saturated fatty acids have been previously removed by lithium salt methods.

EXAMPLE 119

Soybean oil is hydrolyzed in sodium hydroxide methanol under boiling for 1 hour to obtain the fatty acids, which are treated once with urea in methanol to remove saturated fatty acids roughly and treated with thionyl chloride, thereby to obtain soybean oil fatty acid chloride.

Ten grams of thus obtained soybean oil fatty acid chloride is dropped into a benzene solution containing 5 g. of 2-methoxycyclohexylamine and 4 g. of trimethylamine at a temperature of 0° C. to 5° C. while being stirred.

The reaction mixture is stirred for 2 hours at room temperature and for additional 4 hours at 70° C., and a mixture of ice and water is added thereto. The benzene layer is washed successively with 5% hydrochloric acid, 5% sodium bicarbonate aqueous solution and water, and dried over anhydrous sodium sulfate. Upon evaporation of benzene, the residue is distilled in vacuo, thereby to yield 10.3 g. of N-2-methoxycyclohexyl soybean oil fatty

acid amide, B.P. 178-189° C./0.03 mm. Hg, I.V. 125.8. (I.V. means iodine value.)

EXAMPLE 120

60 Safflower oil is transesterified with methanol and the methyl ester is distilled, thereby to obtain the methyl ester of safflower oil, hydrolyzed and chlorinated, thereby to obtain safflower oil fatty acid chloride. Ten grams of thus obtained safflower oil fatty acid chloride is dissolved in 20 ml. of tetrahydrofuran and the solution is dropped into a mixture of 6 g. of m-methylbenzylamine, 5 g. of sodium carbonate and 50 ml. of methyl isobutyl ketone at a temperature of 0° C. to 3° C. while being stirred. 65 The reaction mixture is treated in similar way as in Example 119, thereby to obtain 12.1 g. of N-methylbenzyl safflower oil fatty acid amide, B.P. 200-208° C./0.02 mm. Hg, I.V. 123.5.

70 In similar way as in Examples 119 and 120, the following results are obtained.

Oil	Amine	Solvent	Auxiliary agent for condensation	B.P. ° C./mm. Hg
Example No.:				
121..... Corn oil.....		Acetone.....	K ₂ CO ₃	188-204/0.04
122..... Linseed oil.....		Benzene.....		192-206/0.05

¹ The oil attached with (1) is treated after hydrolysis with lead salts to remove saturated fatty acids.

² The oil attached with (2) is treated after hydrolysis with urea to remove saturated fatty acids.

³ The oil attached with (3) is after hydrolysis recrystallized to remove saturated fatty acids.

EXAMPLE 133

Ten grams of linseed oil and 10 g. of methylamine are stirred in an autoclave at room temperature for 240 hours.

After the reaction is over, the reaction mixture is poured into a mixture of 1 N hydrochloric acid and ice, and subjected to extraction with ethyl ether.

The ether layer is washed successively with 5% hydrochloric acid, 5% sodium carbonate aqueous solution and water, and then dried over sodium sulfate. Upon evaporation of ether, the residue is subjected to fractional distillation in vacuo, thereby to yield 8.9 g. of N-methyl linseed oil fatty acid amide, B.P. 178-190° C./0.03 mm. Hg, I.R. 1,650 cm.⁻¹. (I.R. means wave number of the infrared absorption spectrum.)

EXAMPLE 134

Twenty grams of linseed oil and 10 g. of cyclohexylamine are stirred in an atmosphere of nitrogen for 70 hours at a temperature of 145° C. to 150° C. while being heated. After the reaction is over, the reaction mixture is poured into a mixture of 1 N hydrochloric acid and ice, and subjected to extraction with ethyl ether. The ether

layer is washed successively with 5% hydrochloric acid, 5% sodium carbonate aqueous solution and water, and dried over anhydrous sodium sulfate.

Upon evaporation of ethyl ether, the residue is subjected to careful fractional distillation, thereby to yield 18.2 g. of N-cyclohexyl linseed oil fatty acid amide, B.P. 195-208° C./0.03 mm. Hg.

EXAMPLE 135

Ten grams of safflower oil and 5 g. of o-toluidine are added into a solution of 50 ml. of anhydrous benzene and sodium methylate which is prepared from 1 g. of sodium, and the mixture is stirred in an atmosphere of nitrogen for 5 hours under boiling, and then the reaction mixture is carefully poured into a mixture of 1 N hydrochloric acid and ice.

The solution is treated in similar way in Example 133 or 134, thereby to yield 8.1 g. of N-2-methylphenyl safflower oil fatty acid amide, B.P. 183-215° C./0.03 mm. Hg.

This product is dissolved in petroleum ether and subjected to recrystallization to remove impurities, thereby to yield the product having iodine value of 130.2.

17

EXAMPLE 136

Ten grams of soybean oil and 5 g. of piperidine are stirred in an autoclave for 50 hours at a temperature of 200° C.

The reaction mixture is treated in similar way as in Example 133, thereby to yield 7.3 g. of N-pentamethylene soybean oil fatty acid amide, B.P. 176-213° C./0.03 mm. Hg.

EXAMPLE 137

Ten grams of rice bran oil and 10 g. of 2,4,6-trimethyl-aniline and sodium methylate which is prepared from 1.3 g. of sodium, are stirred in toluene for about 5 hours under boiling, while the formed methanol is continuously removed from the reaction system with rectification column. The reaction mixture is treated in similar way as in Example 133, thereby to yield 9.2 g. of N-2,4,6-trimethylphenyl rice bran oil fatty acid amide, B.P. 181-204° C./0.02 mm. Hg.

EXAMPLE 138

Ten grams of safflower oil and 8 g. of allylamine are stirred in an autoclave for 60 hours at a temperature of 100° C.

The reaction mixture is treated in similar way as in Example 133, thereby to yield 6.9 g. of N-allyl safflower oil fatty acid amide, B.P. 185-199° C./0.02 mm. Hg.

In similar way as in Examples 133 to 138, the following results are obtained.

¹ The reaction is proceeded in an autoclave.

² Impossible to distil.

EXAMPLE 171

Twenty grams of linseed oil and 10 g. of 2-methoxy-cyclohexylamine are mixed and stirred in an atmosphere of nitrogen at a temperature of 135° C. to 140° C. for 40 hours. Then the reaction mixture is distilled in vacuo, thereby to yield 25 g. of N-2-methoxy-cyclohexyl linseed oil fatty acid amide, B.P. 200-209° C./0.02 mm. Hg. I.R. 1650 cm.⁻¹.

EXAMPLE 172

Five and a half grams of sodium methylate is added to a mixture of 20 g. cottonseed oil and 10 g. of 4-methoxy-cyclohexylamine and the mixture is stirred in an atmosphere of nitrogen at a temperature of 140° C. to 150° C. for 1 hour, while formed methanol is continuously removed from the reaction system.

Then the reaction mixture is poured into water and subjected to extraction with ether.

18

The extracted ether layer is washed successively with 5% hydrochloric acid and water, and dried over anhydrous sodium sulfate.

Upon evaporation of ether, the residue is subjected to distillation, thereby to yield 23 g. of N-4-methoxy-cyclohexyl cottonseed oil fatty acid amide, B.P. 189-203° C./0.03 mm. Hg. n_D^{32} 1.4838.

EXAMPLE 173

10 Six grams of sodium ethylate is added to a mixture of 20 g. of safflower oil and 10 g. of 4-ethoxy-cyclohexylamine and the mixture is stirred in an atmosphere of nitrogen at a temperature of 70° C. to 80° C. for 2 hours, while formed ethanol is removed from reaction system in vacuo. Then the reaction mixture is treated in similar way as in Example 172, thereby to yield 24 g. of N-4-ethoxy-cyclohexyl safflower oil fatty acid amide, B.P. 191-208° C./0.02 mm. Hg. n_D^{31} 1.4840, I.V. 110.

This product is subjected to recrystallization with 20 acetone to yield the product having M.P. 30° C. to 34° C., I.V. 135.

EXAMPLE 174

Twenty grams of corn oil and 20 g. of dibenzylamine are dissolved in 100 ml. of toluene and 5.5 g. of sodium methylate is added thereto.

The solution is stirred at a temperature of 90° C. to 100° C. for about 7 hours, while the formed methanol is removed from reaction system. Then the reaction mix-

ture is treated in similar way as in Example 172, thereby to yield 20 g. of N,N-dibenzyl corn oil fatty acid amide, B.P. 190-212° C./0.02 mm. Hg.

EXAMPLE 175

Twenty grams of sesame oil and 10 g. of α -methyl-benzylamine are treated in similar way as in Example 171, thereby to yield 23 g. of N- α -methylbenzyl sesame oil fatty acid amide, B.P. 188-211° C./0.02 mm. Hg.

EXAMPLE 176

Twenty grams of sunflower oil and 10 g. of α -methyl-benzylamine are treated in similar way as in Example 171, thereby to yield 23 g. of N- α -methylbenzyl sunflower oil fatty acid amide, B.P. 188-210° C./0.03 mm. Hg.

EXAMPLE 177

Twenty grams of cuttlefish oil and m-methylbenzylamine are treated in similar way as in Example 171,

thereby to yield 21 g. of N-methylbenzyl cuttlefish oil fatty acid amide, B.P. 191-223° C./0.03 mm. Hg, n_D^{25} 1.5130.

EXAMPLE 178

Twenty grams of shark oil and 10 g. of p-methylbenzyl- 5 amine are treated in similar way as in Example 171, thereby to yield 23 g. of N-p-methylbenzyl shark oil fatty acid amide, B.P. 195-216° C./0.03 mm. Hg.

EXAMPLE 179

Twenty grams of sardine oil and 10 g. of o-methoxybenzylamine are treated in similar way as in Example 171, thereby to yield 22 g. of N-o-methoxybenzyl sardine oil fatty acid amide, B.P. 199-224° C./0.06 mm. Hg. 10

EXAMPLE 180

Twenty grams of cod oil and 10 g. of p-methoxybenzyl- 15 amine are treated in similar way as in Example 171, thereby to yield 13 g. of N-p-methoxybenzyl cod oil fatty acid amide, B.P. 210-220° C./0.03 mm. Hg, n_D^{27} 1.5108, 20 I.V. 280.

EXAMPLE 181

Twenty grams of whale oil and 10 g. of o-hydroxybenzylamine are treated in similar way as in Example 171, 25 thereby to yield 23 g. of N-o-hydroxybenzyl whale oil fatty acid amide, B.P. 179-203° C./0.03 mm. Hg.

EXAMPLE 182

Twenty grams of flatfish oil and 10 g. of m-methoxy- 30 cyclohexylamine are treated in similar way as in Example 171, thereby to yield 22 g. of N-m-methoxycyclohexyl flatfish oil fatty acid amide, B.P. 188-211° C./0.03 mm. Hg.

EXAMPLE 183

A mixture of 10 g. of methyl ester of safflower oil fatty acid and 5 g. of cyclohexylamine is treated in similar way as in Example 171, thereby to yield 10 g. of N-cyclohexyl safflower oil fatty acid amide, B.P. 186-210° C./0.02 mm. Hg. 40

EXAMPLE 184

A mixture of 10 g. of methyl ester of cuttlefish oil fatty acid, from which saturated fatty acid has been roughly removed with urea and methanol, and 5 g. of α -methylbenzylamine is treated in similar way as in Example 171, 45 thereby to yield 10 g. of N-(α -methylbenzyl) cuttlefish oil fatty acid amide, B.P. 178-204° C./0.02 mm. Hg.

EXAMPLE 185

Twenty grams of safflower oil methyl ester from which has been roughly removed saturated fatty acid methyl ester by urea method and 10 g. of cyclohexylamine are treated in similar way as in Example 171, thereby to yield 24 g. of N-cyclohexyl safflower oil fatty acid amide. B.P. 190-198° C./0.03 mm. Hg. 50

The effectiveness of the present natural fatty acid amide derivatives are set forth below.

Fatty acid amide derivatives of Example No.	Blood cholesterol indexes (10 days)	
	1% administered	0.2% administered
None	100	
Linoleic acid	75-80	100-105
1	70	85
3	32	61
7	63	89
13	63	87
14	35	52
16	41	58
18		85
20	70	85

The effectiveness of these compounds were tested in mice which were fed a synthetic diet enriched with cholesterol and bile acids. The serum cholesterol level of the mice had been elevated 3 to 6 times the normal level. The natural fatty acid amide derivatives were well mixed in the synthetic diet in 1% or 0.2% amount, and fed ad libitum for a 10 day period. Then the total cholesterol value in the blood serum of the animals was determined. The value was calculated as a percentage of the serum cholesterol level of a simultaneous control group to obtain the blood cholesterol index.

The extremely low toxicities of the present fatty acid amide compounds, which are one of the features of the present invention, were confirmed by acute and chronic toxicity studies carried out on laboratory animals. As a result of the acute toxicity test, it was found that none of these compounds has any significant toxic effect on mice even when administered in such dosages as 50 g./kg. of the body weight. In the chronic toxicity test, no significant toxic effect or mortality was observed when rats were placed on a commercial diet supplemented with N-cyclohexyl safflower oil fatty acid amide or N-cyclohexyl sardine oil fatty acid amide at levels of 2%, 1% or 0.5% for 6 months. There was no observed difference in body weight gain compared with that of the control group and no detectable change was found upon hematological and histological examination.

The cholesterol-lowering agent of this invention may be orally administered. Usually the oral dose is 0.1-20 g. per day, preferably 0.5-5 g. per day and the administration may be continued for 1-5 months, usually for about 3 months. The cholesterol-lowering agent may be in any suitable form which is conventional for oral administration. Thus, it may be encased in a capsule, in 70 a liquid form, in a tablet form, or in a powder form.

21

In preparing the agents in these various forms, the active compound may be mixed with or impregnated in a suitable solid carrier, or it may be mixed with a liquid carrier such as edible oil, preferably those containing linoleic acid. It is also possible to use a mixture of two or more kinds of the N-substituted natural fatty acid amide of the invention.

What we claim is:

1. An N-substituted natural fatty acid amide represented by the formula

wherein R^1 stands for a natural fatty acid residue, said natural fatty acid being the fatty acid of an oil selected from the group consisting of soybean oil, cuttlefish oil, sesame oil and safflower oil.

2. N- α -methylbenzyl soybean oil fatty acid amide.
3. N- α -methylbenzyl sesame oil fatty acid amide.
4. N-(α -methylbenzyl)cuttlefish oil fatty acid amide.
